CLOTHES WASHING APPARATUS

Bernard E. Brown, Chicago, Ill., assignor to General Electric Company, a corporation of New York

Application October 29, 1957, Serial No. 693,135

7 Claims. (Cl. 68—24)

This invention relates to clothes washing apparatus and more particularly it relates to structures for use in the drums of clothes washing machines in which cleaning liquids are removed from clothes and other fabrics by a high speed centrifuging operation.

A considerable number of domestic clothes washing machines include a perforated drum or basket adapted for rotation about a horizontal axis, in which clothes or other fabrics are subjected to a series of washing, rinsing, and centrifugal extraction operations. These operations are often facilitated by the provision of lifts or vanes circumferentially spaced around the inside of the drum wall to lift and tumble the clothes during drum rotation.

During the washing operation the fabrics are tumbled at a relatively low speed in the presence of water and usually a detergent. After conclusion of the washing operation, the fabrics are subjected to a rinse or series of rinses in water, often in conjunction with a rinsing agent. When the rinsing operation is concluded, the rinse water is then extracted from the fabrics by a centrifuging or spin operation in which the drum is rotated at a relatively high speed, forcing the water to leave the fabrics and escape from the drum through its perforations. In practice, it has been found advantageous to interrupt this spin operation by one or more pause or rest periods during the spin cycle.

The so-called combination washer-dryer machine performs all of the above operations and in addition provides a heat drying operation after the spin cycle. In these machines, after the extraction operation, the machine completes drying by circulating heated air through the fabrics while they are being continuously tumbled in the drum.

Horizontal axis washers and combination washer-dryers possess many advantages and have achieved wide acceptance. However, they also have a disadvantage in that the fabric articles undergoing washing tend to adhere or "plaster" to the inside wall of the drum during the spin operation. During spin, the wet fabric articles are thrown into contact with and become tightly pressed against the drum periphery while the water is being extracted. Consequently, after completion of the spin cycle, it is usual that some of the clothes and other fabric articles remain tightly pressed against the inside wall of the drum. This tight adhesion of the clothes is such that a portion of the clothes will cling to the drum wall even though the spin operation is interrupted by pause periods and is followed by a tumbling cycle. The tendency to adhere to the drum wall is even more pronounced when the articles being washed are relatively small and light such as diapers, handkerchiefs, and gloves.

The clothes and other fabric articles which have adhered to the drum wall can be removed by hand after spin without difficulty if the machine is an ordinary washer. However, if the machine happens to be a combination washer-dryer, a more serious problem is presented. Under ordinary conditions in the combination washer-dryer, the lifting and tumbling of the clothes and

2

other fabrics during the heated drying operation prevents heat damage to the fabrics because no particular area of the fabric is subjected to a prolonged heated period. However, if one of the fabric articles undergoing drying should remain adhered to the drum wall throughout the typical drying period, the fabric may sustain damage from overheating because under these conditions at least a portion of the fabric article may be exposed to the heat source throughout the entire drying cycle.

Accordingly, one object of my invention is to provide for use in combination washer-dryers and horizontal axis clothes washers, structures which automatically dislodge clothes and other fabric articles from the drum wall after a spin operation, thereby preventing damage to the articles by eliminating the adhesion thereof to the drum wall.

It is another object of my invention to provide a simple, inexpensive structure which is easily assembled into the drum of a horizontal axis clothes washer and which is automatically effective to free fabric articles which have adhered to the inside wall of the drum during a clothes washing centrifuging operation.

It is still another object of my invention to provide means as above described, which may easily be installed in a conventional washing machine drum, thus making available to older machines the advantages of automatic fabric dislodgment provided by my invention.

Briefly stated, in accord with the illustrated embodiments of my invention, I provide a series of the fabric-dislodging devices about the inner periphery of a drum of a horizontal axis washing machine. The devices may preferably comprise suitably shaped wire structures secured to the drum by means of enlarged end portions which are inserted through suitable openings in the drum periphery in a manner which permits the structures movement relative to the drum side wall. In general, the structures will lie adjacent the drum periphery underneath clothes being treated within the drum. During the relatively high speed centrifuging operation, the structures and the fabrics disposed thereon will be in close proximity to the drum wall throughout the drum's rotational orbit due to the magnitude of the centrifugal force acting upon the structures and the fabrics. However, at slower speeds, with correspondingly lower centrifugal force, or during a pause period which interrupts the centrifuging operation, the structures will be displaced from the drum wall due to gravitational pull on the structures and fabrics disposed thereon aided by the resilience of the wire structures themselves. The maximum displacement, of course, will occur when a particular structure is at the top of the drum's rotational orbit, for there, gravitational pull on the fabrics and the structures on which they rest is at a maximum. This displacement of each of the structures in turn will carry with it fabrics disposed thereon and is therefore effective to dislodge fabric articles which may have adhered to the drum wall during the centrifuging operation.

The subject matter which I regard as my invention is particularly pointed out and distinctly claimed in the concluding portion of this specification. My invention, however, both as to organization and method of operation, together with further objects and advantages thereof may best be understood by reference to the following description taken in connection with the accompanying drawings in which:

Fig. 1 is a vertical sectional view of a washing machine constructed in accordance with the invention;

Fig. 2 is a transverse sectional view of the drum structure of the machine shown in Fig. 1 taken along the line 2—2 of Fig. 1;

Fig. 3 is an enlarged perspective view of one of the

article-dislodging structures of Fig. 1 before installation in a drum;

Fig. 4 is an enlarged transverse sectional view of a fragment of the drum structure of the machine shown in Fig. 1 with broken lines showing the position of the structures corresponding with centrifuging operation of the drum;

Fig. 5 is a view showing a second form of article-dislodging structure;

Fig. 6 is an enlarged transverse sectional view of a fragment of a drum structure incorporating the structure of Fig. 5 with broken lines showing the position of the structure corresponding with centrifuging operation of the drum; and

Fig. 7 is an enlarged perspective view of the drum structure of Fig. 6 showing the drum periphery openings into which the enlarged ends of the article-dislodging structures are inserted for securement.

Referring now to the drawings, in Fig. 1 I have shown the invention incorporated in a horizontal axis washing machine 1 of the domestic type which includes a suitably mounted tub assembly or liquid container 2 having an access opening 3 in the front thereof which is in registration with an outer access opening 4 in the housing or cabinet 5. The space between the outer access opening 4 and the tub access opening 3 is bridged by a suitable rubber sleeve 6. The outer access opening 4 is closed by a watertight door 7.

Within tub assembly 2 is a cylindrical perforated drum 8 which contains the clothes and other fabrics 9 during the various operations of the clothes washing machine. The drum 8 is adapted for rotation in one direction and includes a side wall 10 having a plurality of perforations 11 therein, a front wall 12 and a back wall 13. The front wall 12 is formed with an access opening 14 in registration with the access opening 3 in the tub assembly 2.

Disposed within the drum are a plurality of circumferentially spaced, ridge shaped vanes 15 to lift and tumble the clothes 9 during the various treating operations within the machine.

Also within the drum against the inside of wall 10 are a plurality of article-dislodging structures 16 having body portions 17. In a preferred embodiment as shown in Fig. 1, these structures are formed of relatively stiff, resilient, wire having the general shape shown in Fig. 3, and are assembled in the drum in co-operating pairs which are disposed in close proximity to and parallel with the drum wall in the bay areas between adjacent tumbling vanes. For securement, structures 16 have enlarged ends 18, which may be loops formed by a bending operation, which are individually inserted in openings 11 in drum side wall 10. The inherent stiffness of structures 16 is such that once assembled to the drum, in the absence of exterior force, they will substantially constitute chords which intersect the curve formed by the drum side wall 10. However, the structures 16 will readily deform when subjected to a force. In my preferred embodiment the structures 16 are somewhat longer than the minimum distance between the edges of the openings 11 in which the enlarged ends 18 are inserted. This extra length permits the body portions 17 to substantially conform to the drum side wall periphery when the structures are subjected to small degrees of radially directed force. However, when such a force is removed, the resilience of the structures 16 will cause them to return to their normal chord relationship with the drum side wall. As shown in Figs. 1, 2, and 4, in a preferred form the structures 16 are considerably shorter than the distance between adjacent vanes and are mounted in parallel pairs in a staggered arrangement with the ends of alternate structures 16 in circumferential registration. This permits the structures 16 to cover the major portion of the drum area between vanes while body portions 17 maintain a close relationship with the drum side wall 10. As the structures 16 will yield under small force, are of rela-

tively small cross section, and are closely disposed against the drum wall, there is practically no departure from normal conditions with the drum. In the subject embodiment, I have obtained good results in regard to stiffness, resilience and freedom from corrosion with wire structures fabricated from 0.036" diameter stainless steel spring wire, American Iron and Steel Institute Type 302.

The drum 8 is mounted for rotation by means of a shaft 20 which is journaled in bearings (not shown) in a transmission housing 21. Within the housing 21 is a suitable two-speed transmission (not shown) which may be similar to that disclosed in U. S. Patent 2,426,078, issued August 19, 1947, to Rex Earl Bassett, Jr. As the transmission forms no part of this invention, its description has been omitted for the sake of brevity. The transmission housing 21 is carried by means of diverging stampings or similar spaced members 22 and 23 forming the rear wall of the tub assembly 2.

The transmission contained in housing 21 is provided with a pulley 24 driven by a belt 25 from pulley 26 on the armature shaft of an electric drive motor 27 which is attached in depending fashion from tub assembly 2.

Secured in suitable fashion to the rear wall of transmission housing 21 is a solenoid 28 which is adapted to shift the drum 8 from low or tumble speed to high or centrifuging speed on energization. This is accomplished when the solenoid 28 actuates engagement gears (not shown) forming a high speed drive within the housing 21. During washing, rinsing, and drying operations, the drum is rotated at a relatively low or tumble speed, for example, 54 R. P. M. On energization of the solenoid 28, the transmission within the housing 21 will be actuated so that the drum 8 will begin to rotate at a relatively high or centrifuging speed, for example, 365 R. P. M. It will be obvious, of course, that centrifugal forces acting upon objects within the drum will be much higher during the centrifuging operation than during slower speed operations of the drum.

It will be understood that with the transmission as described, the drum will rotate in the same direction during all phases of the complete washing machine cycle, but my invention is equally applicable to washing machines in which the drum rotates in one direction during the washing or tumbling operation and in the opposite direction during the centrifugal extraction operation.

Water is supplied to the tub assembly 2 through a water inlet hose 30 under control of a suitable electrically operated water inlet valve 31. The inlet hose 30 is connected to hot and cold water sources through valves (not shown) so that water of suitable temperature may be admitted to the tub.

The washing liquid is discharged from the tub through water discharge hose 32 to a suitable drain (not shown) under control of an electrically operated washing liquid discharge valve 33.

It will be understood that in the sequence of operations, which will be described hereinafter, the various elements of the washing machine, such as the motor 27, the solenoid 28, the water inlet valve 31 and the washing liquid discharge valve 33 may be automatically controlled from a central source as by means of an electric timer actuated switch mechanism (not shown). Such control systems are well known in the art and further description thereof is deemed unnecessary since they form no part of the instant invention.

The operation of a clothes washing machine embodying the invention begins when the clothes 9 and a suitable detergent are inserted in the drum 8 through access opening 4. Water of the proper temperature is then admitted to the tub from the inlet hose 30 controlled by the electrically operated valve 31. It will be understood that the solenoid is not energized and therefore the transmission within housing 21 will be adjusted for tumbling speed. The motor 27 is then energized and rotation of the drum begins.

During tumbling rotation, the clothes 9 are continuously carried from the lower part of the drum upwardly by the vanes 15 to a point where they fall to return to a lower part of the drum. On the drawings I have shown only four vanes and eight wire structures between adjacent vanes for simplicity. However, it will be understood that a greater or lesser number of vanes or wire structures as desired can be used within the machine.

After the washing machine operation is complete, the washing liquid is drained from the machine through the discharge hose 32 controlled by the electrically operated valve 33. Then, clean rinse water is admitted to the machine through water inlet hose 30 controlled by inlet valve 31 and the clothes or other fabrics undergoing washing are subjected to one or more rinses.

After the rinse part of the cycle is complete, the transmission within housing 25 is actuated to the relatively high centrifuging speed by the energization of solenoid 28. Due to the high centrifugal forces acting on objects in the drum during the centrifuging operation, the fabrics and the wire structures on which they are disposed lie very close to the periphery of the drum side wall at this time. While the centrifuging operation proceeds, rinse water from within the drum and the fabrics flows out of the drum through its perforations. After leaving the drum, the water is then drained from the machine through the discharge hose 32 controlled by the electrically operated valve 33.

During the centrifuging operation, the drum rotation is interrupted by one or more pause or rest periods in which the drum comes to a complete stop. As the drum slows to a stop, the centrifugal forces acting upon the fabrics within the drum and the wire structures 16 against which they are disposed are progressively eliminated. Thereupon, the resilience of the wire structures 16, aided by gravitational forces acting upon the fabrics and the structures themselves in the upper portion of the drum's rotational orbit, will cause wire structures 16 to assume their normal chord relationship with the drum side wall and thus to be displaced radially inwardly away from the drum side wall periphery. As the wire structures move away from the drum, they will carry with them fabrics which were pressed tightly against the wire structures and the drum side wall. The fabrics 9 will thus be dislodged from the drum side wall periphery and are free to fall to the lower part of the drum. Thereafter, if the machine cycle calls for further tumbling operations the fabrics will be freely lifted and tumbled by the vanes as the drum rotation proceeds.

I have found that substantially no tangling of the fabrics during washing operations results from the use of my invention, due to the fact that the wire structures do not move appreciably relative to the fabrics except during periods of slow drum rotation at upper positions on the drum's rotational orbit where fabrics tend to fall downwardly away from the structures rather than to move under them.

Means can also be provided within housing 5 to blow heated air through the clothes 9 during a tumbling operation preceded by a pause period following the centrifuging cycle. If such means are provided, of course, the machine would be classed as a combination washer-dryer. As described hereinbefore, in such a machine the invention will also operate during periods of slow rotation to dislodge any clothes or other fabrics which have adhered to the drum periphery. Thus, there will be no possibility of heat damage to clothes caused by prolonged exposure to heated air through adhesion of particular fabric areas to the drum periphery.

In Fig. 5, I have illustrated a modification of my invention in which a plurality of individual wire members are suitably joined into grid assemblies 34 before installation into a drum 35 having tumbling vanes 36. Grid assemblies 34, which are advantageously also of A. I. S. I. Type 302 stainless steel spring wire, are provided with

resilient side members 37 having end portions 38 which pass through key hole openings 40 located in the tumbling vane portions 36. The end portions terminate in enlarged heads 39, which may be fixed thereto in any suitable manner. The openings 40 include elongated slotted portions 41 which flare out into circular apertures 42 which are located in the drum periphery along the junction between the side wall of drum 35 and the vanes 36. The proportions of the openings 40 are such that the heads 39 will freely pass through apertures 42 but are too large to pass through slotted portions 41. On installation of the grid assemblies 34 into the drum 35, the resilient side members 37 are manually flexed toward the drum side wall to bring the end portions 38 into registration with apertures 42. The heads 39 are then projected through the wall of drum 35 through apertures 42. When the flexing force is released from side members 37, their resilience will move the enlarged ends out of registration with apertures 42. Under normal washing machine conditions within the drum, the grid assembly side members 37 will travel in the slotted portions 41. Consequently, the grid assemblies 34 will be retained within the drum because the heads 39 are too large to pass through the slotted portions 41.

When centrifuging operations are taking place within the drum 35, the grid assemblies 34 will assume positions against the drum side wall as indicated by the broken lines in Fig. 6 due to the high centrifugal forces acting on objects within the drum at this time. However, as the drum slows to a stop, as just before a pause period, the centrifugal forces acting upon the fabrics and grid assemblies 34 will be progressively reduced. Thereupon, gravitational forces acting upon the grid assemblies 34, as they reach upper portions of the drum's rotational orbit, will cause them to progressively fall away from the drum side wall to assume positions at the inner part of the slotted portions 41 as shown by the solid line representation in Fig. 6. As the grid assemblies 34 move away from the drum side wall, they will carry with them fabrics which were tightly pressed against the side wall of the drum during centrifuging. Thus the fabrics will be dislodged from the drum side wall to fall to the lower part of the drum. Thereafter, if the machine cycle calls for further tumbling operations the fabrics will be freely lifted and tumbled by the vanes as the drum rotation proceeds.

While I have shown two embodiments of the invention, it will be understood that it is not so limited, but is subject to other modifications, and it is intended to cover in the appended claims all such modifications as fall within the scope of the invention.

I claim:

1. In apparatus for washing and drying fabrics by operations including a high speed centrifuging extraction operation, the combination comprising: a substantially cylindrical perforated drum to contain the fabrics, said drum being rotatable about a horizontal axis; a plurality of mutually spaced vanes extending inwardly from said drum parallel to the axis of rotation of said drum, said vanes being adapted to lift and tumble the fabrics during washing and drying operations of the apparatus; a plurality of wire structures secured within said drum adjacent the cylindrical wall thereof intermediate each adjacent pair of vanes, whereby the respective structures are interposed between the fabrics and the side wall of the drum, the opposite ends of each of said structures freely projecting through openings in said drum permitting said structures movement radially of said drum; and means for rotating said drum at a centrifuging speed whereby the respective structures and fabrics disposed thereon will move outwardly into close proximity to the drum wall for the escape of liquid from said fabrics, said structures, upon interruption of rotation of said drum, moving inwardly away from said drum wall urged by gravitational force acting on said

structure and said fabrics, thereby dislodging fabrics which may have adhered to the drum wall interior during the centrifuging operation.

2. In apparatus for washing and drying fabrics by operations including a high speed centrifuging extraction operation, the combination comprising: a substantially cylindrical drum to contain the fabrics, said drum having a perforated side wall; means for mounting said drum for rotation about a horizontal axis; a plurality of mutually spaced vanes extending inwardly from said drum parallel to the axis of rotation of said drum, said vanes being adapted to lift and tumble the fabrics during washing and drying operations; a plurality of mutually spaced pairs of elongated, resilient wire structures movably disposed within said drum about the cylindrical wall thereof, whereby the respective structures are interposed between the fabrics and the side wall of the drum, the respective structures extending generally parallel to each other and normal to said vanes, end portions of each of said structures freely projecting through one of said drum perforations, means at the extremities of said structures for retaining said structures within said drum during rotation thereof while permitting radial movement of said structures relative to said drum; and means for rotating said drum at a high centrifuging speed whereby the respective structures and fabrics disposed thereon will move outwardly into close proximity to the drum wall due to the large magnitude of the centrifugal force associated with said centrifuging speed and the resulting flexure of said wire structures, said structures, upon interruption of rotation of said drum, moving inwardly away from said drum wall due to the resilience of said structures and gravitational force acting on said structures and said fabrics, thereby dislodging any fabrics which may have adhered to the drum wall interior during the centrifuging operation.

3. In apparatus for washing and drying fabrics by operations including a high speed centrifuging operation, the combination comprising: a substantially cylindrical perforated drum to contain the fabrics; means for mounting said drum for rotation about an axis inclined from the vertical; a plurality of wire grid-like structures movably disposed contiguous to the inside of said drum cylindrical wall, whereby the respective structures are interposed between the fabrics and the side wall of the drum, each of said structures having end portions freely projecting through openings in said drum, said openings being oversize relative to said end portions to permit said structures a desired degree of movement relative to said drum, enlarged head members at the extremities of said end portions for preventing the escape of said end portions through said openings; and means including a drive motor to rotate said drum at a centrifuging speed whereby the respective structures and fabrics disposed thereon will move outwardly into close proximity to the drum wall due to the large magnitude of the centrifugal force associated with said centrifuging speed, certain of said grid structures, upon substantial reduction in the speed of rotation of the drum, moving inwardly away from said drum wall urged by gravitational force acting on said grid structures and said fabrics, thereby dislodging any fabrics which may have adhered to the drum wall interior during the centrifuging operation.

4. In apparatus for washing and drying fabrics by operations including a high speed centrifuging extraction operation, the combination comprising: a drum to contain the fabrics; means for mounting said drum for rotation about a horizontal axis, said drum having a generally cylindrical perforated side wall and an access opening to receive said fabrics; a plurality of elongated, deformable, resilient wire structures movably disposed within said drum about the cylindrical wall thereof, whereby the respective structures are interposed between the fabrics and the drum, the respective structures substantially form-

ing chords intersecting said drum side wall and extending generally parallel to each other and normal to said vanes, each of said structures having its end portions freely projecting through one of said drum side wall perforations, 5 said ends having loops, whereby when said structures are moved relative to the drum side wall, said structures will be retained within said drum because of interference between said looped ends and the periphery of said perforations; and means including a drive motor to rotate said drum at a high centrifuging speed whereby the fabrics disposed on said structures will move radially outwardly urged by the magnitude of the centrifugal force associated with said centrifuging speed and thereby flex said resilient structures so that the fabrics will be in close proximity to the drum wall; said structures, upon interruption of said centrifuging operation to slow said drum to a stop, moving inwardly away from said drum wall due to the resilience of said structures and gravitational force acting on said structures and said fabrics, thereby dislodging any fabrics which may have adhered to the drum wall interior during the centrifuging operation.

5. In apparatus for washing and drying fabrics by operations including tumbling operations and a high speed centrifuging extraction operation, the combination comprising: a substantially cylindrical, perforated drum to contain said fabrics, said drum being arranged for rotation about an axis inclined from the vertical and having an access opening to receive said fabrics; a plurality of mutually spaced vanes extending inwardly from said drum side wall parallel to the axis of rotation of said drum to lift and tumble the fabrics during certain of the operations of the machine, said vanes having radial slotted openings; wire grid structures of approximately rectangular configuration movably disposed contiguous with and generally parallel to the inside of said drum wall intermediate each adjacent pair of vanes and occupying a large proportion of the drum area therebetween, whereby the respective structures are interposed between the fabrics and the side wall of the drum, each of said grid structures having side members with end portions freely projecting through said slotted openings, whereby said grid structures are permitted radial movement relative to said drum as permitted by the radial length of said slotted openings; means at the terminals of said end portions having a diameter 30 greater than the width of said openings to maintain the said end portions in the said relationship with said slotted openings during the rotation of said drum; means including a drive motor to rotate said drum at a centrifuging speed whereby the respective grid structures and fabrics disposed thereon will move outwardly so as to be in close proximity to the drum wall under the influence of the centrifugal force engendered by said centrifuging speed, and upon interruption of said centrifuging rotation so as to bring said drum to a stop, some of said grid structures will be urged by gravity inwardly away from said drum wall to dislodge fabrics which may have adhered to the drum wall interior during the centrifuging operation.

6. In apparatus for washing and drying fabrics by operations including a high speed centrifuging extraction operation, the combination comprising: a perforated, clothes-containing drum rotatable about a horizontal axis, said drum having a perforated generally cylindrical side wall and an access opening to receive said fabrics; a plurality of elongated, deformable, resilient structures 60 having hooked end portions in engagement with certain of the drum side wall perforations, whereby said structures are movably mounted within said drum adjacent to its side wall, so as to be interposed between the fabrics and the side wall of the drum, said structures being retained within said drum by means of said end portions, the respective structures moving outward into close proximity to said drum side wall when subjected to radially directed force but springing away from said drum side wall when said force is removed; and means including a

drive motor to rotate said drum at a high centrifuging speed whereby the fabrics disposed on said structures will move radially outwardly urged by the large magnitude of the centrifugal force associated with said centrifuging speed deforming said structures so that the fabrics will be in close proximity to the drum wall and at slow speeds with correspondingly low centrifugal force whereby said structures will spring inwardly away from said drum wall due to the resilience of said structures aided by gravitational force acting on said structures and said fabrics, thereby dislodging any fabrics which may have adhered to the drum wall interior during the centrifuging operation.

7. In apparatus for washing and drying operations on fabrics including a high speed centrifuging extraction operation the combination comprising: a perforated drum rotatable about an axis inclined to the vertical to contain the fabrics to be treated said drum having a generally cylindrical side wall and an access opening to receive said fabrics; at least one grid structure mounted within said drum contiguous with and generally parallel to said side

wall, whereby the structure is interposed between the fabrics and the side wall of the drum, said structure being of high specific gravity relative to said fabrics and having two opposite end portions movably attached to said drum, 5 permitting said structure to move outwardly to or inwardly away from said drum side wall, each of said end portions being movable substantially equal distances relative to said side wall; and means for rotating said drum at a high centrifuging speed whereby the structure and fabrics disposed thereon will move outwardly into close proximity to the drum side wall under the influence of the centrifugal force engendered by said centrifuging speed, said structure, upon interruption of centrifuging rotation of said drum, moving inwardly away from said drum wall 10 while traversing upper positions on the drum's rotational orbit under the influence of gravitational force acting on said structure and said fabrics, thereby dislodging any fabrics which may have adhered to the drum wall interior during centrifuging operation.
